UNITED STATES PATENT OFFICE.

ANDREW JOHNSEN, OF VANCOUVER, BRITISH COLUMBIA, CANADA.

MEANS FOR CONNECTING THE ENDS OF LIFTING-ROPES TOGETHER UNDER THE HULL OF A SUBMERGED VESSEL.

1,240,979.

Specification of Letters Patent. Patented Sept. 25, 1917.

Application filed January 26, 1917. Serial No. 144,723.

To all whom it may concern:

Be it known that I, ANDREW JOHNSEN, a citizen of the Dominion of Canada, residing at Vancouver, in the Province of 5 British Columbia, Canada, have invented certain new and useful Improvements in Means for Connecting the Ends of Lifting-Ropes Together Under the Hull of a Submerged Vessel, of which the following

10 is a specification.

This invention relates to a means for connecting wire ropes together beneath the hull of a submerged vessel and is designed to enable such to be done in a depth of 15 water where it may be inconvenient or impossible for divers to descend, so that sunken vessels may be lifted therefrom.

The invention comprises a strongly constructed pair of tongs of such size that 20 when the points are closed together they will encircle the cross section of the vessel to be raised. The ends of the wire rope which it is desired to connect together under the submerged vessel are removably 25 connected to each opposed end of the tongs, and means are provided that when these ends are brought together, as when the tongs are closed, they automatically lock one to the other, so that the ropes are definitely 30 connected together. To render the tongs available for passing further ropes under the hull, the act of connecting the rope ends together releases their attachment to the ends of the tongs.

35 The tongs are lowered by wire ropes to the submerged wreck from the salvage vessel on the surface, the ropes being so connected to the tongs, that while being lowered the tongs will hang in the open position.

40 When they attain the desired position on the wall of the submerged vessel other wire ropes connected to the tongs are drawn in to close the points of the tongs on one another under the wreck and thereby connect 45 the ropes.

A water service under pressure is delivered to each member of the tongs that a jet may be projected from its end to clear the way for it through the silt or gravel on 50 which the submerged vessel may rest.

The invention is particularly described in the following specification, reference being made to the drawings by which it is accompanied, in which:

55 Figure 1 is a longitudinal section on the

line 1—1 in Fig. 2 of the tong end shoes by which the lifting wire ropes are passed under the hull of a submerged vessel and connected together, the same being shown as they approach one another to connect. 60

Fig. 2 is a sectional plan of the same on the line 2—2 in Fig. 1.

Fig. 3 is a cross section on the line 3—3 in Fig. 2.

Fig. 4, a cross section on the line 4—4 65 in Fig. 2.

Fig. 5 is a profile to a smaller scale of the tongs as applied to lift a submerged vessel, the dot and dash lines showing them as lowered to it, and the full lines as closed 70 to encircle its cross section, and connect the lifting lines under it, and

Fig. 6 is a plan to an enlarged scale of the pivotal connection of the two tong members. 75

In these drawings 2 and 3 represent the ends of two steel wire ropes which are preferably applied in pairs that they may pass over opposite sides of the lifting pontoons. The ends of 2 are connected at 4 in a female 80 locking shoe 6, and the ends of the other ropes 3 are secured at 5 to a male locking member 7 which is adapted to enter the socket 8 of the female shoe 6.

Vertically movable within the socket 8 85 of the female shoe is a lock bolt 10 adapted to pass vertically downward through an aperture 9 provided in the male member 7, after its insertion in the socket 8, and secure it therein. This lock bolt 10 downwardly 90 projects from the middle of a member having a rack 12 projecting downward from each end parallel with the lock bolt. This lock bolt is normally maintained in the upward position, to be clear of the socket, in 95 a manner to be described later. It is moved downward through the aperture 9 of the male member 7 by geared segments 14 on a rocking member which is pivotally mounted in the sides of the female shoe 6. 100

The teeth of these segments engage those of the racks 12 of the lock member and intermediate of the segments the rocking member has arms 16 which, when the lock bolt 10 is toward the upper limit of its 105 movement project downward in the path of the bevels 11 on each side of the male member 7, as it passes into the socket 8, and being engaged by them the rocking member is rotated and its segments 14 pro- 110

ject the lock bolt 10 through the aperture 9 of the member 7.

The tongs 20, 21 by which the self-locking member 6, 7, to which the ends of the cable 2 and 3 are connected, are passed under the hull and pressed together to effect connection of the rope, are shaped to encircle, when closed, the cross section of the vessel to be lifted. They are pivotally connected together at 22, and from each corner 24 where the tong members 20 and 21 are shaped to pass down the side of the vessel, struts 23 are pin-connected to the tong members and to one another at 25 above the middle line. To each pin 24 or adjacent thereto wire ropes 27 are connected, by which the tongs may be lowered to the submerged vessel, the preponderating weight of the horizontal components of the tong members tending to hold the tongs open, as shown by the dot and dash lines in Fig. 5.

On the pin-connection 22 of the tong members and on the pin-connection 25 of the struts, sheaves are mounted around which the wire rope 26 is passed by which the pivot 22 may be drawn up toward 25 to close the points of the tongs.

To each corner of the tong members adjacent the pin-connection 24 of the struts a flexible hose pipe 28 delivers water under pressure which is conducted to the point of the tongs, either through a pipe or through the hollow of the tongs where the construction of the tong members allow it.

The male connecting member 7 is carried within a shoe 13 resembling 6, and both shoes 13 and 6 are removably connected to the opposed ends of the tongs 20, 21 by bolts 15 which are projected from the shoes through apertures in the top and bottom slideways of the tong ends. The inner ends of the opposite bolts 15 of each shoe 6 and 13 are connected together within each shoe 45 by a pair of toggle levers 17 and to the middle pivot of each lever system is connected a sleeve 18 through which slidably pass pipes 30 and 31 which are telescopically connected to the water service pipe of each 50 tong member.

The pipe 30 which serves the male member 7 extends above that member through its shoe 13 to a short distance from its outer end, so that when the member 7 is inserted 55 in the socket of the female shoe the end of the pipe will engage the end of that shoe and be pushed back.

Similarly, the water jet pipe 31 of the female shoe is produced into contact with 60 the inner shoulder of the socket aperture 8 and has a butting block 33 secured on its end to engage the point of the male member 7 when the same is inserted in the socket 8. Thus, as the male and female coupling 65 ends of the lifting wire rope are connected

together, the water jet pipes 30 and 31 are pressed back and adjacent the inner limit of their movement, a collar 32 secured on each will engage the sleeves 18 and move each toggle lever system backward to withdraw the lock bolt 15 and release the shoes 13 and 6 from the ends of the toggle levers 20 and 21.

The butting block 33, when in its normal position at the forward limit of its movement, sustains the lock bolt 10 above the socket aperture 8 until as the butting block is pressed back by the male member 7 the locking bolt 10 is free to be moved down and into the aperture 9 of the male member 80 in the manner previously described.

In use, the tongs 20, 21 with the ends of the lifting ropes 2 and 3 connected to their ends by the shoes 6 and 13, are lowered from the salvage vessel on the surface across 85 the hull of the submerged vessel, the position of which has previously been accurately determined.

The tongs being lowered by the lines 27 will hang in the open position, as shown by the dot and dash lines in Fig. 90

5. When the tongs are across the hull the water service is delivered through the flexible pipes 28 to the tong members and is projected from the jet pipes 30, 31 and the line 26 is drawn in to close the points of 95

the tongs beneath the hull of the vessel, the jets of water clearing the way for the points of the tongs. As the points close on one another the male member 7 enters the socket 100

8 of the female member and the lock bolt 10 of the female member is forcibly passed through the aperture 9 of the male member 7, see Figs. 1 and 2, to secure the two ends 105

of the lifting ropes 2 and 3 together. Simultaneously the backward movement of the water pipes 30, 31 acting through the system of toggle levers 17 of each tong end 110

shoe 6 and 13 withdraws the bolts 15 and releases the tong ends from the shoes. By slacking the line 26 and lifting on the lines 115 27 the points of the tongs are withdrawn from the shoes leaving them connecting the lifting ropes 2 and 3 under the hull of the boat, while the tongs may be removed to effect the junction of other ropes at other 120 places along the hull.

Having now particularly described my invention, I hereby declare that what I claim as new and desire to be protected in by Letters Patent, is:

1. A means for automatically connecting together the ends of wire lifting ropes beneath the hull of a submerged vessel, said means comprising coupling members, instruments for bringing said coupling members 125 together into the coupling position, and means for releasing said instruments from said coupling members upon completing the coupling act.

2. A means for automatically connecting 130

- together the ends of wire lifting ropes beneath the hull of a vessel submerged in a depth of water inaccessible to divers, said means comprising coupling members, instruments for bringing said coupling members together into the coupling position, and means for releasing said instruments from said coupling members upon completing the coupling act.
- 10 3. A means for automatically connecting together the ends of wire ropes, said means comprising a socket member secured to the end of one rope, a spigot member secured to the end of the other, means coöperative with insertion of the spigot in the socket for securing it therein and members engaging the said socket and spigot members by which the same may be moved together to the coupling position.
- 15 4. A means for automatically connecting together the ends of wire ropes, said means comprising a socket member secured to the end of one rope, a spigot member secured to the end of the other, and a lock member within the socket of one rope to engage and secure the spigot member of the other, means normally holding said lock member retracted, said holding means adapted for engagement by said spigot member upon insertion to move said lock member into locking engagement with the spigot member.
- 20 5. A means for automatically connecting together the ends of wire ropes, said means comprising a socket member secured to the end of one rope, a normally retracted lock bolt movable across the socket aperture within the socket, a spigot member secured to the other rope end, said spigot aperture to receive the lock bolt of the socket member when inserted, and means whereby insertion of the spigot in the socket projects the lock bolt to secure it therein.
- 25 6. A means for automatically connecting together the ends of wire lifting ropes under water, said means comprising a socket member secured to the end of one rope, a spigot member secured to the end of the other rope, means within the socket member for securing the spigot member when the same is inserted, means for removably connecting the spigoted and socketed ends of the ropes to the opposed ends of a pair of tongs, and means for opening and closing the tongs below water.
- 30 7. A means for automatically connecting together the ends of wire lifting ropes under water, said means comprising a socket member secured to the end of one rope, a spigot member secured to the end of the other rope, means within the socket member for securing the spigot member when inserted, means for removably connecting the spigoted and socketed ends of the ropes to the opposed ends of a pair of tongs, and means for opening and closing the tongs below water, said means comprising a wire rope connected to each tong member between its pivot and its end, and a wire rope connected to the pivot.
- 35 8. A means for automatically connecting together the ends of wire lifting ropes under water, said means comprising a socket member secured to the end of one rope, a spigot member secured to the end of the other rope, means within the socket member for securing the spigot member when the same is inserted, means for removably connecting the spigoted and socketed ends of the ropes to the opposed ends of a pair of tongs, means for opening and closing the tongs below water, said means comprising a wire rope connected to each tong member between its pivot and its end, and a wire rope connected to the pivot, and means coöperative with the insertion of the spigot within the socket for disconnecting the spigoted and socketed ends of the lifting ropes from the tong ends.
- 40 9. A means for automatically connecting together the ends of wire ropes, said means comprising a socket member secured to the end of one rope, a spigot member secured to the end of the other, and a lock member within the socket of one rope to engage and secure the spigot member of the other, said lock member moved into locking engagement by insertion of the spigot member, means for removably connecting the spigoted and socketed ends of the lifting ropes to the opposed ends of a pivotally connected pair of tongs having struts pivotally connected to the tong members on each side of their pivot, which struts are pivotally connected together above the joint of the pivot of the tongs, a wire rope connected to each tong member adjacent the connection of the strut members thereto, a wire rope taking around sheaves on the pivot of the tongs and on the pivot connecting the strut members together, and means coöperative with the closing of the spigoted and fauceted ends of the lifting ropes together for releasing said spigoted and fauceted ends from the tong ends.
- 45 10. A means for automatically connecting together the ends of wire lifting ropes, said means comprising, a spigot member secured to the end of one rope, a socket member secured to the end of the other rope, said socket member having a lock bolt operative by insertion of the spigot of the other rope whereby when the spigot is inserted it will be locked in the inserted position, a pair of tongs pivotally connected together at one end, a pair of struts pivotally connected together above the pivot of the tongs, the other end of each strut pivotally connected to each tong member intermediate of its ends, a wire rope connected to each tong member adjacent the pivotal connection of the strut thereto, so

that when the tongs are suspended by these ropes the tongs will hang open, a wire rope passing around sheaves on the tong pivot and sheaves on the connecting pivot of the struts to one another whereby when suspended on this rope the points of the tongs will be closed on one another, and means for removably connecting the spigoted end of one lifting rope and the socket end of 10 the other lifting rope respectively to the opposed ends of the tongs, and means whereby when the tongs are moved into connecting engagement the spigoted and socketed ends of the lifting ropes will be released from 15 their connection to the tong ends.

11. A means for automatically connecting together the ends of wire lifting ropes under water, said means comprising a socket member secured to the end of one rope, a spigot member secured to the end of the other rope, means within the socket member for securing the spigot member when the same is inserted, means for removably connecting the spigoted and socketed ends of the ropes to 20 the opposed ends of a pair of tongs, means for opening and closing the tongs below water, and a water service flexibly connected to each member of the tongs and conducted 25

to jet pipes adjacent the opposed ends of the tongs. 30

12. A means for automatically connecting together the ends of wire lifting ropes under water, said means comprising automatically locking male and female coupling members secured to the respective ends of 35 the ropes, applying instruments for carrying said coupling members beneath the vessel into coupling engagement, means for locking said coupling members to said applying members and means operated by the coupling together of said coupling members for releasing said connecting means whereby 40 said applying members may be withdrawn from said coupling members.

13. The combination with the male and 45 female coupling members each including shoes, of applying instruments engaging said shoes, toggle latches for connecting said applying instruments to said shoes and releasing members adapted to be operated 50 during the coupling act for breaking the toggles to withdraw the toggle latches whereby said applying members may be disconnected from said shoes.

In testimony whereof I affix my signature. 55
ANDREW JOHNSEN.
